WILLIAM STANNUS, OF DETROIT, MICHIGAN, ASSIGNOR TO STANNUS PROPELLER CORPORATION, OF DETROIT, MICHIGAN, A CORPORATION OF MICHIGAN

SCREW PROPELLER

Application filed February 20, 1930. Serial No. 429,909.

The present invention relates to water-craft screw propellers having driving and dragging surfaces designed to eliminate characteristics tending to reduce propulsive capacity, formation of the blade being such that loss of efficiency because of radial divergence of water due to centrifugal action is practically eliminated. In other words, none of the rearwardly-acting thrust of the propeller is lost through movement or displacement of water in any direction other than parallel to the propeller hub axis.

It may be said that no water is projected from the blade of my propeller in other than an approximately horizontal direction, loss of efficiency due to carrying water with the blades and radial projection therefrom at tips being eliminated.

My invention is embodied in screw propeller blades of a radial thickness gradually decreasing from root to tip of blade, with working or propelling-force faces formed by a slightly curved generatrix, the forward, or drag, faces being stream lined to reduce frictional resistance to rotation while insuring sufficient strength to withstand deformation due to thrust stress.

Attainment of extremely high efficiency is the chief object to be accomplished by this invention, which involves practical application of the principles of stream-line design to propeller blades of a contour such that, beginning at about one-third of the blade length from axis, the effective propulsive area of the blade decreases as the distance from the axis increases, so that along equally-spaced concentric arcuate lines on the force faces of the blades, the propulsive force exerted is uniform or, in other words, the force-distance ratio for about two-thirds of the blade length is practically constant. The thrust on the water along any line at all points equidistant from the propeller axis is of practically unvarying value from leading

45 to trailing edge of blade, stream lining of the

drag, or forward, side of each blade serving to minimize resistance to rotative movement of the blades.

The "working" surface or "force" face of each blade being such as would be formed by 50 a curved generatrix positionally conforming to the pitch desired, all points equidistant from the propeller axis in a curved line traced on the force face of each blade by a point traveling at uniform rate in a path parallel 55 to the propeller axis lie in the same plane set at pitch angle to axis.

Of the accompanying drawings, wherein all reference figures have the same application and significance,

Figure 1 is an elevation, or projection on a plane at right angles to the vertically disposed hub axis, showing how the propeller looks when viewed from the forward, or drag, side of the blades;

Fig. 2 is an elevation, or projection on a plane parallel to the horizontally-disposed hub axis, showing how the propeller looks when viewing the force face of one blade (upper) and drag side of the other (lower) 70 blade, this view being at right angles to that shown in Fig. 1 and showing how both leading and trailing edges of the blades project beyond the forward and rearward faces 75 of the hub;

Fig. 3 is an end view indicating the sweep of the blades as seen when looking towards the tip of one blade and showing to what extent both the leading and following edges 80 thereof project beyond the forward and rearward faces of the hub;

Fig. 4 is a sectional view showing a radial cross section from root to edge of one blade along line 4-4 of Fig. 2, the edge of blade being rounded off, as indicated, on the forward or drag side;

Fig. 5 is a cross-sectional view taken on a line 5-5 near the root of the blade, where the contour is such as to minimize mere

"churning" of the water, thereby making propeller more efficient; and

5 Figs. 6, 7, and 8 are blade sections taken on correspondingly numbered lines of Fig. 1 and showing the stream line contour of each blade, the thickness of which at any given point is considerably less than is characteristic of ordinary propeller blades at corresponding points. These sectional views also 10 give an idea of the variations in contour of the blades, as indicated by width from leading to trailing edges.

15 As herein illustratively disclosed by Figs. 1 and 2, my invention is embodied in a screw propeller having but two opposed radial blades, but it is equally applicable to three and four-blade propellers, the blades having curved and stream-lined leading and trailing edges 1 and 2, the tip of blades being indicated by Figure 3 and hub by 4, the force face 20 of blade by 5 and forward, or drag, side of blade by 6.

25 Being of uniform pitch, the force face 5 of each blade corresponds to that of a true screw, stream lining for reducing resistance to movement of the blade through the water as the propeller turns being confined to the forward, or drag, side 6 of each blade, which, as indicated by Fig. 4, is comparatively thin 30 at the tip 3, the area of radial cross section or radial thickness of blade increasing gradually from tip to root in proportion to the stress withstood, and from this maximum radial thickness the metal tapers away to 35 both leading and following edges, 1 and 2, which are rounded off, as indicated by Figs. 6, 7, and 8, which are sectional views taken along the axial arc 6, 7, and 8 of Fig. 1.

40 The force faces of the blades are not radially straight, as would be the case if they corresponded to the line A—B of Fig. 4, but, as indicated, are of concave arcuate outline, departure from a straight radial line not only having a counteracting influence on the 45 diverging effect of centrifugal force developed by rotation of the propeller but serving also to reduce the torque requirement for a given boat speed.

45 The thick part of each blade follows an 50 imaginary line roughly corresponding to the contour of the leading edge and running approximately parallel therewith at about one-third of the distance between the leading and following edges of the blade.

55 The accompanying illustrations show a propeller having hub and blades integrally cast, but my invention may equally well be embodied in blades cast separately from the hub and having at their inner ends suitable 60 lugs for use in bolting them to a hub adapted to receive them.

What I claim is:

65 1. A watercraft propeller blade of unsymmetrical stream-line cross section, having its thickest portion disposed along an imaginary

line directionally corresponding approximately to that of a line representing the leading-edge contour of the blade and located at about one third of the distance between the leading and following edges of blades, said 70 edges being of arcuate contour.

2. A watercraft propeller blade of unsymmetrical cross section, having a concave working or force face surface and a convex drag surface, the latter being stream lined from 75 root to tip along an imaginary maximum thickness line approximately paralleling the leading-edge contour, the area of blade from a position approximating one-third of the blade length from hub axis decreasing gradually towards curved tip of blade, the edges of which are of arcuate contour and rounded off on the drag side, substantially as shown and described.

3. A watercraft screw propeller having a 85 series of radially arranged blades diagonally disposed with reference to the axis of the hub, said blades having concave working or force-face surfaces and convex drag-side surfaces, the latter being so stream lined as to produce 90 an unsymmetrical disposition of the material of which the blade is made, the thickest part of each blade being located about one third of the width of the blade from its leading edge and approximately parallel 95 thereto from root to tip, the material tapering in both directions from the imaginary line of maximum blade thickness to the leading and following edges of said blades, said edges being rounded off on the drag side of 100 each blade, and having a curvilinear contour such that as the distance from the axis increases the width of the blade correspondingly decreases so as to make possible the maintenance of an approximately uniform force-distance ratio on the outer two-thirds of the 105 working surface of the blade.

4. A watercraft screw propeller having a plurality of radially-disposed blades of stream-line unsymmetrical cross section and 110 of uniform true-screw pitch, of such contour, or outline, that the propulsive, or force-face, area of each blade decreases as the distance from the propeller axis increases, so that from the tip inwardly to a position approximately one-third of the length of blade away from the propeller axis the propulsive force extended along concentric arcs of varying axial radii is of practically unvarying value, the blades having slightly concaved force 115 faces, with drag faces tapering both ways from an imaginary line of maximum thickness approximately parallel to the leading edge of each blade.

5. A watercraft screw propeller having 125 a plurality of radially-disposed blades with concave helical force-face surfaces and convex drag-face surfaces, said blades having an unsymmetrical stream-line cross section, the maximum axial thickness of blade 130

following an imaginary radially disposed line
approximately parallel to the leading edge
of blade at a distance therefrom equal to
about one-third of the blade width, each blade
5 having a contour such that the force-face, or
propulsive, area decreases as the distance
from the axis increases, thereby equalizing
distribution of propulsive stress and mak-
ing feasible the use of comparatively thin
10 blades projecting beyond the fore and aft
faces of propeller hub and tapering both
ways from the stream-lining point of maxi-
mum blade thickness.

In testimony whereof I affix my signature.
